MUFFLE-FURNACE.

1,195,641.

Specification of Letters Patent. Patented Aug. 22, 1916

Application filed March 18, 1916. Serial No. 85,150.

To all whom it may concern:

Be it known that we, GEORGE W. BATCHELL and JAMES H. WADE, citizens of the United States, residing, respectively, at Cincinnati, county of Hamilton, State of Ohio, and Moundsville, in the county of Marshall and State of West Virginia, have invented a new and useful Muffle-Furnace, of which the following is a specification.

10 This invention has reference to muffle furnaces of the down draft type, and particularly adapted for annealing purposes.

The object of the invention is to equalize and conserve the heat and distribute it about 15 the articles or ware being annealed.

The invention comprises a furnace with a muffle chamber or oven surrounded by flues leading from a fire chamber about the oven from alternately opposite sides and 20 discharging into a common flue ultimately leading to the stack. Each flue of the series extending about the oven from opposite sides is provided with an individual damper, and exterior to the alternately arranged flues 25 provision is made for heat insulation, whereby loss of heat by radiation is to a great extent prevented.

The invention will be best understood from a consideration of the following detailed 30 description, taken in connection with the accompanying drawings forming part of this specification, with the further understanding that while the drawings show a practical form of the invention, the latter 35 is not confined to any strict conformity with the showing of the drawings, but may be changed and modified so long as such changes and modifications come within the scope of the appended claims.

40 In the drawings: Figure 1 is a longitudinal vertical section of the improved furnace. Fig. 2 is a section on the line 2—2 of Fig. 1 but omitting one side of the furnace. Fig. 3 is a cross-section of the furnace through 45 one of the series of alternating heating flues. Fig. 4 is a section on the line 4—4 of Fig. 3.

Referring to the drawings, there is shown a basic structure 1 which may be made of some refractory material, such, for instance, 50 as fire brick. This basic structure has side walls 2 rising above it and joined by an arch 3. Exterior to the lower portions of the side walls 3 are channel beams 4 on opposite sides of the furnace carried by 55 buckstaves 5 with the latter joined at the

upper ends by connecting rods 6, and also carrying other channel beams 7 at suitable heights. Rising from the beams 4 and continued over the arch 3 is an envelop 8 of heat insulating material covered exteriorly 60 by other walls 9 having a crown portion 10 over that portion of the heat insulating material covering the arch 3.

Within the base 1 and extending lengthwise thereof is a flue 11 constituting the outlet flue and which may be continued to and discharge into a suitable stack, the latter, however, not being shown. Above the flue 11 is another longitudinally extended flue 12 underlying a muffle chamber 13, which latter 70 is located between the side walls 2 and beneath the arch 3. The muffle chamber is provided with an entrance opening 14, which, of course, when the furnace is in operation is closed by suitable means not shown in 75 the drawing.

The flue 12 is entered at one end by a burner 15 which may be assumed to be supplied with suitable fuel through a pipe 16 containing a controlling valve 17. The 80 burner 15 with its supply pipe is representative of any suitable type of burner capable of supplying fuel enough to produce a sufficiently hot flame for the purposes of the furnace. Leading from opposite sides of 85 the flue 12 are other flues 18 contained within the muffle chamber 13. Each flue 18 communicates with a flue 12 through a port or opening 19, and is thence continued up one side of the muffle chamber, beneath the arch 90 3, and down the other side of the muffle chamber, having a continuation 20 into the base 1, and ultimately opening into the flue 11 by way of a port or passage 21. Within the continuation 20 there is lodged a damper 95 plate 22 of some suitable refractory material so arranged as to be movable into traversing relation to the continuation 20 to varying degrees, whereby the passage of hot products of combustion through the flue may be controlled at will. By having the flues 18 with

their uptakes and downtakes on alternately opposite sides of the muffle chamber, there is produced a substantially equal distribution of heat in the muffle chamber, so that 105 the temperature of the chamber is substantially equal throughout. The flues 18 are lodged within the muffle chamber and are separated inwardly from the side walls 2 by spacers 23, whereby all parts of the flues 110

within the muffle chambers are utilized for heat radiation.

The hot products of combustion from the burners or fire chamber end of the flue 12 5 pass beneath the muffle chamber, thence to and up the flues 18 on alternately opposite sides of the chamber, over the top or arch portion of the chamber, and thence downwardly on alternately opposite sides of the 10 chamber, finally discharging downwardly into the outlet flue 11 arranged in the bottom part of the furnace structure, which furnace is, therefore, of the down draft type. The layer 8 of heat insulating material in enveloping relation to the sides and top of the muffle chamber serves to retard radiation of heat from the muffle chamber, wherefore there is but a negligible waste of 15 heat by radiation. For these reasons the 20 muffle furnace of the present invention is economical in operation, and is highly efficient for annealing purposes, since the temperature throughout the muffle structure is sensibly even, and the articles subjected to 25 the annealing temperature are uniformly annealed.

What is claimed is:—

1. A muffle furnace having a muffle chamber with a series of spaced flues contained 30 within the chamber and extending in alternation up one side of said chamber, across the top thereof and down the other side of the chamber, a flue underlying the muffle chamber and communicating with all the 35 flues on the opposite sides of the chamber, said last-named flue having means for the combustion of fuel to produce heat, and an outlet flue underneath the flue underlying the muffle chamber and communicating with 40 all the flues extending through the chamber.

2. A muffle furnace having a muffle chamber with a series of spaced flues contained within the chamber and extending in alternation up one side of said chamber, across 45 the top thereof and down the other side of the chamber, a flue underlying the muffle chamber and communicating with all the flues on the opposite sides of the chamber, said last-named flue having means for the 50 combustion of fuel to produce heat, and an outlet flue underneath the flue underlying the muffle chamber and communicating with all the flues extending through the chamber, said flues extending through the muffle 55 chamber being each provided with a valve or damper individual thereto for controlling the flow of heated products of combustion therethrough.

3. A muffle furnace provided with a muffle 60 chamber, spaced heating flues wholly within the chamber where traversing it and extending up and down opposite sides of said muffle chamber and over the top thereof, a heating flue with means therein for the 65 combustion of fuel and communicating

with the uptake sides of the first-named flues, an outlet flue underlying the heating flue and communicating with the downtake sides of the first-named flues, and a valve or damper in the downtake side of each of the 70 first-named flues and individual thereto.

4. A muffle furnace provided with a muffle chamber with heating flues contained within and traversing said chamber, and heat insulating material lodged within the 75 walls of the muffle chamber in enveloping relation to the sides and top of the chamber.

5. A muffle furnace having a muffle chamber, a heating flue extending beneath the chamber, a series of flues inside of the 80 chamber and spaced apart lengthwise of the series with alternate flues communicating with the respectively opposite sides of the heating flue underneath the chamber, each of the series of flues rising within the chamber 85 along one side of said chamber, extending across the top and down the other side thereof, and an outlet flue into which all of the heating flues within the chamber discharge. 90

6. A muffle furnace having a muffle chamber, a heating flue extending beneath the chamber, a series of flues inside of the chamber and spaced apart lengthwise of the series with alternate flues communicating 95 with the respectively opposite sides of the heating flue underneath the chamber, each of the series of flues rising along and spaced from a respective inner side wall of the chamber, extending across and spaced from the inner wall of the top of the chamber and down and spaced from the inner wall of the other side thereof, and an outlet flue into which all of the heating flues within 100 the chamber discharge, said outlet flue being located beneath the first-named flue. 105

7. A muffle furnace having a muffle chamber, a heating flue extending beneath the chamber, a series of flues inside of the chamber with alternate flues communicating with the respectively opposite sides of the heating flue underneath the chamber, each of the series of flues rising within the chamber along one side of said chamber, extending across the top of the chamber and down the other side thereof, and an outlet flue into which all of the heating flues within the chamber discharge, said outlet flue being located beneath the first-named flue, and the 110 downtake side of each of the series of flues extending through the bottom of the chamber and there provided with a regulating valve or damper individual thereto. 115

8. A muffle furnace provided with a muffle chamber, a primary heating flue underlying the muffle chamber, a series of flues contained within the chamber and each having upright side portions at respectively opposite sides of the chamber in spaced relation to the inner side walls thereof, and a 125 130

- connecting top portion within and extending across the top of the chamber in spaced relation to the inner wall of the top thereof, said flues being connected in alternation to the primary heating flue on respectively opposite sides thereof, and an outlet flue below the primary heating flue with the series of flues extended through the bottom of the chamber and connected in alternation to respectively opposite sides thereof. 5
9. A muffle furnace provided with a muffle chamber, a primary heating flue underlying the muffle chamber, a series of flues each having upright side portions at respectively opposite sides of the chamber in spaced relation to the side walls thereof, and a connecting top portion extending across the top of the chamber in spaced relation to the top wall thereof, said flues being connected in alternation to the primary heating flue on respectively opposite sides thereof, and an outlet flue below the primary heating flue with the series of flues connected in alternation to respectively opposite sides thereof, 15
- 20 said furnace having heat insulating material embedded in its walls along the sides and over the top of the muffle chamber.
10. A muffle furnace having a muffle chamber with a series of heat conducting flues contained within said chamber, and a primary heating flue underlying the chamber, the flues within the chamber being spaced apart in the direction of the length of the series and connected in alternation 25 from the bottom of the muffle chamber to respectively opposite sides of the primary heating flue underneath the muffle chamber. 30
11. A muffle furnace provided with a muffle chamber, means for directing heat primarily beneath the chamber, and means contained within the chamber in spaced relation to the inner walls thereof for directing heat from beneath the chamber up each side thereof, across the top, and down the 40 opposite side of the chamber from the rising movements of the heat. 45
12. A muffle furnace having a muffle chamber with heating flues interior to and in spaced relation to the inner side and top walls of the chamber, each flue alternating with the adjacent flues with respect to the direction of movement of the heating medium therethrough. 50
13. A muffle furnace having a muffle chamber with heating flues therein in spaced relation to the side and top walls of the chamber, each flue alternating with the adjacent flues with respect to the direction of movement of the heating medium therethrough, said furnace having a heating flue communicating with the intake sides of the flues within the muffle chamber and extending beneath the floor of the muffle chamber. 55
14. A muffle furnace having a muffle chamber with heating flues therein in spaced relation to the side and top walls of the chamber, each flue alternating with the adjacent flues with respect to the direction of movement of the heating medium therethrough, said furnace having a heating flue 60 communicating with the intake sides of the flues within the muffle chamber and extending beneath the floor of the muffle chamber, and said furnace also being provided with an escape flue for the heating element communicating with the outlet sides of the flues within the muffle chamber, said last-named sides of the flue within the muffle chamber extending downwardly to the point of communication with the common outlet flue. 65
15. A muffle furnace provided with an escape flue, a primary heating flue and a muffle chamber in superposed order, with the sides and top wall of the muffle chamber having heat insulating material embedded therein in enveloping relation to the sides and top of the muffle chamber, and a series of heating flues in the muffle chamber in spaced relation to the top and side walls of said muffle chamber, said last-named flues being connected on alternately opposite sides of the muffle chamber with the primary heating flue and on the corresponding other side of the chamber with the outlet flue. 70
